UNITED STATES PATENT OFFICE.

LOUIS WILPUTTE, OF JOLIET, ILLINOIS.

COKE-OVEN DOOR.

1,006,036.

Specification of Letters Patent. Patented Oct. 17, 1911.

Original application filed November 30, 1910, Serial No. 594,942. Divided and this application filed March 9, 1911. Serial No. 613,353.

To all whom it may concern:

Be it known that I, Louis Wilputte, a subject of the Kingdom of Great Britain, residing in Joliet, in the county of Will and 5 State of Illinois, have invented a new and useful Improvement in Coke-Oven Doors, of which the following is a specification.

This application is a division of application No. 594,942 for coke ovens filed by this 10 applicant November 30, 1910.

This invention relates to improvements in the construction and operation of the double doors for coke-ovens, and the invention consists in the novel parts, and combinations of parts and devices, hereinafter 15 particularly described, set forth, shown, and claimed.

In the accompanying drawings which form a part of this specification, Figure 1 20 is a front view of a coke-oven showing a face view of the outer door, applied and sealed; Fig. 2 is a sectional view on the line 2—2 of Fig. 1, a portion being added to the section above the limits of said Fig. 1; 25 Fig. 3 is a cross section on the line 3—3 of Fig. 1, the section being, however, upon a larger scale than said Fig. 1; Fig. 4 is a face view of the outer door with the cotter bars removed therefrom; Fig. 5 is a fragmentary view of the face of the inner door showing its two pivoted latches.

In said drawing 11 is the inferior of the oven; 12 the flooring thereof, 13 the mouth or door opening of said oven, made with an 35 opening somewhat flaring to more readily receive and center the plug door. This plug-door, or inner door, consists of the rectangular frame, 14, having the inwardly projecting flange, 15, extending entirely 40 around the door, to receive and retain the fire-brick lining 16, and having the laterally projecting flange 17 to set against the face 18 of the door masonry jamb at the top and sides of the door. At the bottom of the 45 plug-door its metal frame is made with an opening through to receive the single plug brick 19. This opening is intended for the introduction of an oil or gas burner in the preliminary heating of the oven, the burner 50 being thrust through and burned until the oven is preliminarily warmed, after which the burner is withdrawn and the plug brick inserted closing the opening previous to the filling of the oven with coal for coking. 20, 55 20 show the usual buck-stays of the oven.

21, 21 are two brackets one at each side of and below the door opening. These brackets are secured to the buck-stays. Surrounding the door opening is a metal jamb 22, secured to the brackets 21. The inner 60 lateral face of this jamb is grooved as at 23. Upon the face of the plug door are secured lifting sockets 24, 24, to receive the lifting hooks of, preferably, a suitable twin crane to be used for opening and closing the doors 65 by a lifting and withdrawing action. Pivot- 70 ed to the face of the plug door at each of the said sockets 24 are the latches 25 to en- gage the groove 23 in the jamb to hold the plug door in place. The lower edge of these 75 latches 24 extend far enough below the downwardly opening mouth of the sockets 24 so that when the lifting hooks engage said sockets the latches, by this act, will be lifted, or turned upon their pivots, and un- 75 latched from the groove 23. One of the latches 25 engages the jamb at one side, and the other at the other side, of the door, as will be understood from Fig. 5.

We now go to a description of the outer 80 door. This outer door, 26, is a metallic one, made with an inwardly projecting sharp flange 27, all around at the sides and top and bottom, adapted to encounter an asbestos or other packing cushion 28 placed 85 preferably in a groove, 29, in the outer face of the door jamb 22. On the outer face of this door are the lifting sockets, 30, similar to the sockets upon the outer face of the plug door, and for the same purpose, namely 90 to receive the lifting hooks for the removal of the door. Cotter-bars, 31, are loosely attached to the door by pins 32, so as to have a movement to some extent toward and away from the door. The ends of these 95 cotter bars extend at each side beyond the sides of the door, and far enough to engage the upwardly pointing hooks, 33, secured to each side of the door jamb 22. At the center of each cotter-bar is a screw, 34, which may 100 have a square head, 35, to receive a removable operating crank, 36. This screw is tapped into the cotter bar and opposite to it in the face of the door is the shallow cavity 37 to receive the point of the screw. 105

When the outer door is to be set in place, it is first placed, by the lifting hooks, into approximate position, the cotter bars being above the side hooks. The door is then lowered until the projections, 40, at the 110

bottom strike against the brackets 21 which serve to center or position the door vertically. The lateral precise positioning of the door is accomplished in this act of lowering by the wedge shaped projections 41. (See Fig. 4.) These projections are made wedge shaped narrowing from above downward and project from both sides of the door to encounter the sides of the hooks, 33, as the door is being lowered, and thus move laterally, from one side or the other, until it is exactly centered. The door, as will be seen, is thus centered at the top and bottom and sides so that its inwardly projecting sharp flange is brought against the asbestos packing always in exactly the same place. This insures a perfect seal, no matter whether the metallic parts may have warped, or not; because the impression having been made in the packing remains the same and the door is always brought to and so fits it. When the door is in proper position the screws are turned forcing the ends of the cotter-bars out against the retaining hooks and the edges of the flange of the door against the packing thus forming a perfect joint.

I claim:

1. The coke-oven closure comprising in combination an unattached inner plug door and an unattached outer door, means for sealing said outer door and both applicable and removable by a bodily lateral movement and entirely detachable from the oven, substantially as specified.

2. The coke-oven closure comprising in combination, an unattached inner plug door and an unattached outer sealing door, both applicable and removable by a bodily lateral movement and entirely detachable from the oven, the inner plug door being furnished with fire-brick insulation and the outer door being provided with a continuous sealing flange adapted to set against a packing on the door jamb, substantially as specified.

3. The coke-oven closure comprising in combination, an unattached inner plug door and an unattached outer sealing door, both applicable and removable by a bodily lateral movement and entirely detachable from the oven, the inner plug door being furnished with fire-brick insulation and the outer door being provided with a continuous sealing flange adapted to set against a pack-

ing on the door jamb, the inner plug door being furnished with fire brick insulation and with latches taking into the door jambs and the outer door being provided with a continuous sealing flange adapted to set against a packing on the door jamb, and having the set screws and the cotter bars engaging hooks on the jambs for compressing the door to the packing, substantially as specified.

4. The coke-oven closure comprising in combination, an unattached inner plug door and an unattached sealing door both applicable and removable by a bodily lateral movement and entirely detachable from the oven, each of said doors being provided with sockets to receive lifting hooks for applying and removing them, substantially as specified.

5. The unattached coke-oven plug door furnished on its outer face with the lifting hook sockets and applicable and removable by a straight horizontal movement, and provided with the lateral latches, substantially as specified.

6. The unattached coke-oven plug door furnished on its outer face with the lifting hook sockets and applicable and removable by a straight horizontal movement, and provided with the lateral latches, placed adjacent to the hook sockets and in the path of the hook that engages the said socket, substantially as specified.

7. The outer sealing door adapted to be lifted into place and having the centering device consisting of the wedge projections at the sides, whereby the door is laterally adjusted to an exact position as it is being lowered to place, substantially as specified.

8. The outer sealing door adapted to be lifted into place and having the centering device consisting of the wedge projections at the sides, whereby the door is laterally adjusted to an exact position as it is being lowered to place, and the centering projections at the bottom so that the door when placed always occupies the same position and the sealing flange compresses the packing at the same identical groove or place whenever the door is applied, substantially as specified.

LOUIS WILPUTTE.
